UNITED STATES PATENT OFFICE.

CHARLES T. JOSLIN, OF NEW SCOTLAND, NEW YORK.

INVALID-BED.

1,219,558.

Specification of Letters Patent. Patented Mar. 20, 1917.

Application filed June 18, 1913. Serial No. 774,359.

To all whom it may concern:

Be it known that I, CHARLES T. JOSLIN, a citizen of the United States, residing at the town of New Scotland, in the county of 5 Albany and State of New York, have invented certain new and useful Improvements in Invalid-Beds, of which the following is a specification.

My invention relates to beds for invalids 10 and the objects of my invention are to construct a bed which may be easily and smoothly operated and which may assume different positions without jolting the patient and be solid and strong in these positions. Other objects of my invention will be disclosed as I proceed with my specification.

I accomplish these objects by means of the mechanism illustrated in the accompanying 20 drawings in which—

Figure 1 is a plan view of my bed.

Fig. 2 is an end elevation with the bed in ordinary position on the floor.

Fig. 3 is an end elevation with the bed 25 tilted to one side.

Figs. 4 and 5 are detailed views of the standards that support the frame.

Fig. 6 is a side elevation with the bed in ordinary position on the floor and the top 30 of the bed level.

Fig. 7 is a side elevation with the parts broken away and showing the bed tilted end- 35 wise.

Fig. 8 is a longitudinal section showing the bed formed into a chair.

Figs. 9 and 10 are details showing the means for holding up the cot.

Figs. 11 and 12 are details showing the hand wheels for operating the rods.

40 Similar numerals refer to similar parts throughout the several views.

United States Patent No. 882,641, dated March 24, 1908, was issued to me for invalid beds. My present invention is an improvement 45 upon the bed shown in said patent.

Referring to the drawings:—1 is the frame of the bed. 2 is the canvas stretched over the frame as will be hereafter more particularly described.

50 The frame 1 is pivotally mounted on the pedestal 300; pedestal 300 being composed of the bases 5, 5—standards 3, 3 and cross bar 4, which parts are rigidly fastened together. The bases 5, 5 are provided with

casters adapted to rest upon the floor and 55 follow the movement of the pedestal 300.

Rod 29, one end of which is hinged to the pedestal at 30, the other end being hinged at 27° to the adjustable sleeve 27 on the rod 26 fastened to the sides of the 60 frame 1 permits of adjustment of the frame 1. A wing or thumb nut 28 is provided to fasten the sleeve 27 when the frame 1 has been tilted to the desired angle, as shown in Fig 7.

On each side of the pedestal 300 is mounted an auxiliary base 100 which can be forced down by turning the threaded post 7, which will lift one side of the pedestal and tilt the pedestal and frame, as shown in Fig. 3.

The construction of the auxiliary base is as follows:

To the base piece is rigidly fastened a hollow standard 101, on the upper end of which is rigidly fastened the sleeve 6 adapted to engage with and slide upon the standard 3 of the pedestal 300. The sleeve 6 is threaded and acts as a nut for the threaded post 7. The threaded post 7 is provided with collars 70—71 between which the 80 forked piece 1a on the pedestal 300 rests.

The handle 8 is adapted to engage with and drive the threaded post 7; by applying the handle the threaded post 7 may be rotated and the auxiliary base forced down- 85 ward raising the pedestal 300, or by reversing the motion the pedestal 300 may be lowered.

The frame 1 is pivoted at 80 to the pedestal 300.

Mounted crosswise of the frame 1 are shafts 13, 14 and 16 operated, respectively, by the hand wheels 9—10—12, and mounted longitudinally in the frame 1 is the shaft 15 operated by the hand wheel 11.

Hand wheels 9—10—11—12 have, on the inner side of the hubs, notched portions which are adapted to be engaged by the pawls 21—22—23—24.

Hinged to the frame 1 at points 51—51 is 100 a bent bar 50 to which are pivoted the braces 34, which may be used to prop the bar 50 in any desired position, as shown in Fig. 8. To bar 50 is securely fastened one end, and a portion of both edges, of the 105 canvas 2. Other portions of the edges being fastened directly to the frame 1, as shown in Fig. 1. The other end of canvas 2 being fas-

tened to the shaft or rod 14 in such a manner that the rotating of shaft 14 will cause the canvas 2 to be wound thereon or unwound therefrom.

5 Canvas 2 is of sufficient length to permit of a loop being formed, as shown in Fig. 8, when some of the canvas is unwound from shaft 14 by releasing the pawl 22 from engagement with the hand wheel 10 and permitting a reverse movement of said shaft.

10 In Fig. 8 the bed is shown so that an occupant would be in a sitting position; weight being supported on end of cot suspended under canvas, (method of suspending cot will be described later). The portion of canvas stretched across bent bar 50 forming a support for occupant's back and the loop shown permitting occupant's feet to hang down. The end of the canvas attached 15 to the rod 14 is here shown stretched taut to form a table on which any desired articles may be placed within easy reach of the occupant. This portion of canvas being stretched taut by providing suitable loops 20 or a pocket, in which a rod 150 may be slipped; the ends of the rod 150 resting in suitable notches (not shown) in the frame 1—when portion of canvas between rod 150 and shaft 14 may be made taut by winding 25 any slack onto shaft 14 and dropping pawl 22 into engagement thus preventing the unwinding motion.

Underneath canvas 2 is arranged a strip 30 of canvas 25, one end of which is fastened 35 to the side of the frame 1, the other end being fastened to the shaft 15 in such manner that revolving said shaft will cause canvas strip 25 to be wound upon or unwound from said shaft.

40 As thus arranged, the canvas strip comes under an opening provided in canvas 2 and when the excess length of canvas strip is unwound on shaft 15 the opening is covered and extra support offered to any weight 45 which may be placed at a point over the strip. By turning wheel 11 in the proper direction the canvas strip 25 may be loosened to permit the placing of a suitable vessel under the opening provided in canvas 50 2. The canvas strip may also be utilized to support said vessel.

Underneath the frame 1 is suspended a cot and mattress. The cot preferably consists of a rigid metal frame having a woven wire 55 spring 17 and folding legs 31, 31 hinged to the cot frame at 32, 32, which are held either 33—33. The folding legs are provided with rollers.

The cot is suspended under the frame of 60 open or folded by means of suitable braces the bed by means of suitable straps or tapes 18 provided with snaps 19 adapted to hook onto the cot at the desired points, suitable places being provided therefor. In one end 65 of the cot at either side are arranged sliding

rods 20 arranged so that they may be extended a limited distance to provide for the withdrawal of the cot to the position shown in Fig. 8. The tapes 18—18 are attached to the rods or shafts 13—16 mounted in the 70 frame 1.

As thus arranged, the cot may be readily raised or lowered by turning the hand wheels 9 and 12 so as to give the desired motion:

75 This permits of the weight of the occupant being supported on a comfortable mattress or springs, or the cot may be lowered allowing the occupant to be supported only 80 on the canvas. The cot may then be entirely removed by simply unsnapping the hooks 19.

85 Constructed in this way the bed is economical in manufacturing, strong and durable, easy to operate and solid and substantial either at rest horizontally or at any angle or position at which it may be used. The invalid occupying the same in any of the positions described will be secure and will not be jolted or disturbed in changing 90 the position of the bed and may rest upon the mattress and springs of the cot or in a lying-down or reclining position or sitting up as at a table with the bed in the form of a chair, as may be desired.

95 What I claim as my invention and desire to secure by Letters Patent is,

1. An invalid bed consisting of a frame, a cloth covering said frame, the upper portion of said cloth adjoining the head of the bed attached to iron bars hinged to said frame, means whereby said iron bars may be sustained in a reclining or perpendicular position, the central portion of said cloth covering fixedly attached to the side of the frame, the lower portion of said cloth covering next the foot of the bed being adjustably attached to a revolving rod at the foot of the bed, whereby the same may be relaxed affording space for the feet and legs of the person occupying the bed, the central portion of said cloth being provided with an opening, a cloth under said opening, one end of the same fixedly attached to one side of said frame and the other end adjustably attached to a roller on the opposite side of said frame, means whereby said roller may hold said cloth securely under said opening, and means for releasing said cloth whereby it will hang loose under said opening.

100 2. An invalid bed consisting of a frame, a cloth covering said frame, means whereby the said cloth covering of said frame may be sustained in a reclining or vertical position in the form of a chair, standards at the sides of said frame, screw threads in said standards adapted to receive upright posts, upright posts mounted in said standards with screw threads adapted to mesh with the screw threads of said standards, means for 110 115 120 125 130

- mounting said frame in said standards whereby raising and lowering the standards will raise and lower the frame attached thereto.
- 5 3. In an invalid bed a frame, a cloth covering said frame, means whereby the cloth covering of said frame may be sustained in a reclining or vertical position, standards on the sides of said frame, upright posts mounted in said standards, means for mounting said frame upon said standards, means for raising and lowering said standards whereby said bed carried by said standards may be raised and lowered, 10 rods mounted on the sides of said frame, sleeves fixedly attached to said frame and mounted slidably upon said rods, thumb screws for holding said sleeves at any position along said rods, arms hinged at one end to said sleeves and at the other end to said standards, whereby said 15 bed may be tilted longitudinally and held in position as tilted, a cot mounted under said covering, rods attached to said cot, eyelets in the ends of said rods, means whereby said rods may be extended lengthwise beyond the 20 frame of said cot and means for holding said cot against the bottom of said frame by said rods.
- 15 4. In an invalid bed a frame, a cloth covering said frame, means whereby the cloth covering of said frame may be sustained in a reclining or vertical position, standards on the sides of said frame, upright posts mounted in said standards, means for 25 mounting said frame upon said standards, means for raising and lowering said standards whereby said bed carried by said standards may be raised and lowered, rods mounted on the sides of said frame, sleeves fixedly attached to said frame and 30 mounted slidably upon said rods, thumb screws for holding said sleeves at any position along said rods, whereby said bed may be tilted longitudinally and held in position as tilted, a cot mounted under said covering, rods attached to said cot, eyelets in the ends of said rods, means whereby said rods may be extended lengthwise beyond the 35 frame of said cot, a rod rotatably mounted upon said frame, tapes attached to said rod, means for 40 attaching said tapes to the eyelets in the rods attached to said cot whereby said cot may be held under the central portion of the cloth covering of said frame when said bed is used in the form of a chair, substantially 45 as described for the purposes set forth.
- 45 5. In an invalid bed a frame, a cloth covering said frame, means whereby the cloth covering of said frame may be sustained in a reclining or vertical position, standards on the sides of said frame, upright posts mounted 50 in said standards, means for mounting said frame upon said standards, means for
- raising and lowering said standards whereby said bed carried by said standards may be raised and lowered, rods mounted on the sides of said frame, sleeves fixedly attached to said frame and mounted slidably upon said rods, thumb screws for holding said sleeves at any position along said rods, arms hinged at one end to said sleeves and at the other end to said standards, whereby said bed may be tilted longitudinally and held in position as tilted, a cot mounted under said covering, rods attached to said cot, eyelets in the ends of said rods, means whereby said rods may be extended lengthwise beyond the frame of said cot, a rod rotatably mounted upon said frame, tapes attached to said rod, means for attaching said tapes to the eyelets in the rods attached to said cot whereby said cot may be held under the central portion of the cloth covering of said frame when said bed is used in the form of a chair, substantially as described for the purposes set forth.

In testimony whereof I affix my signature in presence of two witnesses.

CHARLES T. JOSLIN.
